SCAFFOLD SUPPORT

Henry P. Albrecht and Kermit H. Wilson, Minneapolis, Minn., assignors to Wilson-Albrecht Co., Inc., Minneapolis, Minn., a corporation of Minnesota

Application May 1, 1947, Serial No. 745,280

3 Claims. (Cl. 304—10)

1

This invention relates to a scaffold support. While the invention might have many applications, it particularly is designed and illustrated as a support for holding timbers forming a scaffold, which scaffold supports operators for working on the ceiling or walls of a building.

It is an object of this invention to provide a scaffold support comprising an elongated member or bar adapted to extend in horizontal position, the same having at one end means constructed and arranged to be disposed in a wall and having means at its other end comprising a ground-engaging support, said support preferably sloping toward said wall.

It is a further object of the invention to provide a scaffold support comprising a horizontally extending timber-supporting member, means at one end of said member such as an angle bar or T-shaped bar adapted to extend into a wall between the bricks or other members thereof, said member having connected adjacent its other end a vertically extending member adapted to be held in different positions in a supporting member comprising upwardly converging bars which preferably slope toward said wall and are separated quite a distance at their lower ends in a direction substantially parallel to said wall.

It is another object of the invention to provide a scaffold support having a supporting means comprising upwardly converging bars connected so as to be relatively swingable to have their lower ends farther apart or closer together, means for holding said bars in different positions, a vertically extending member secured to the upper ends of said bars and projecting thereabove, a second member carried by said vertically extending member, means for holding said second member in different vertical positions, and a timber-supporting member secured to the top of said second member constructed and arranged to receive joist-like timbers on edge and also to receive joist-like timbers or boards in flat position.

It is more specifically an object of the invention to provide a scaffold support such as set forth in the preceding paragraph in which said vertically extending member is in the form of a cylinder and said second member is movable in said cylinder, said cylinder having circumferentially spaced vertically extending open-ended slots in its upper end and a pin adapted to be placed in any one of a plurality of vertically spaced holes in said second member and disposable in a pair of said slots.

These and other objects and advantages of the invention will be fully set forth in the following

2

description made in connection with the accompanying drawings in which like reference characters refer to similar parts throughout the several views and in which:

Some of the important features of the invention disclosed herein are disclosed and claimed in a copending application filed by us on March 23, 1953, under Serial No. 343,814.

Fig. 1 is a view in side elevation of a scaffold support embodying the present invention, certain parts being shown in vertical section, said view also showing a portion of a wall and a portion of a scaffold in vertical section;

Fig. 2 is a top plan view of the device shown in Fig. 1;

Fig. 3 is a horizontal section taken substantially on line 3—3 of Fig. 1, as indicated by the arrows;

Fig. 4 is a horizontal section taken substantially on line 4—4 of Fig. 1, as indicated by the arrows;

Fig. 5 is a partial view in perspective showing one end of the device disposed in a wall;

Fig. 6 is a partial view in side elevation of a modified form of support;

Fig. 7 is a top plan view of Fig. 6;

Fig. 8 is a partial perspective view of some of the parts;

Fig. 9 is a partial view in side elevation of some of the parts; as is also Fig. 9a;

Fig. 10 is a partial view in front elevation of another form of the invention;

Fig. 11 is a view in side elevation of Fig. 10;

Fig. 12 is a vertical section through the upper end of the device;

Fig. 13 is a view in horizontal section taken substantially on line 13—13 of Fig. 11 and shown on a reduced scale;

Fig. 14 is a partial view in perspective showing the upper end of the device including timbers therein;

Fig. 15 is a view in vertical section taken substantially on line 15—15 of Fig. 14, as indicated by the arrows;

Fig. 16 is a partial view in vertical section of a portion of the device;

Fig. 17 is a horizontal section taken on line 17—17 of Fig. 16, as indicated by the arrows; and

Fig. 18 is a perspective view of a clip used.

Referring to the drawings, particularly Figs. 1 to 5, a scaffold support is shown comprising an elongated member 20 adapted to be disposed in horizontal position. While member 20 might take various forms, in the embodiment of the invention illustrated it is shown as a T-bar having

its flange extending horizontally and its central web extending vertically downward. Member 20 has secured to one end thereof a member 21. While member 21 could be variously formed, it is illustrated as a T-bar having the top of its flange resting on top of the flange of member 20 and having its central web extending vertically. Member 21 is thus in inverted position relative to member 20. Member 21 is constructed and arranged to be conveniently disposed in a wall 22 of a building. The vertical web 21a thereof can conveniently be disposed between the ends of a pair of bricks 22a forming said wall and the side portions of the flange 21b can conveniently be disposed between the adjacent side of vertically adjacent bricks. This is clearly shown in Fig. 5. The end of member 20 can abut the outer surface of wall 22, as shown in Fig. 1. A vertically extending member 24 is provided and while this might take various forms, in the embodiment of the invention it is shown as a cylindrical member and specifically as a pipe. A clip 25 shown as formed of a pair of flat steel plates are secured to pipe 24 in any suitable manner, as by welding. Clip 25 has spaced sides 25b projecting at one side of pipe 24 and these are disposed at either side of the web 20a of member 20 and secured thereto in any suitable manner, as by the rivet 26. Member 24 has a slot in its upper end receiving flange 20a. Member 24 is disposed in and slidably in another cylindrical member 27. Member 27 has formed in its top a plurality of vertically extending slots 27a open at their upper ends. Member 24 is provided with a series of vertically spaced holes 24a. A pin 28 is adapted to be disposed in any one of the holes 24a and to be received in a pair of oppositely disposed slots 27a. Slots 27a are circumferentially spaced and four of these are shown 90 degrees apart. A ground-engaging support 30 is provided and while this might be variously formed, in the embodiment of the invention illustrated it comprises upwardly converging members or bars 30a having their upper ends engaging the sides of member 27. A yoke 31 which is illustrated as formed from a rod has its ends extending across one side of members 30a respectively and secured thereto in any suitable manner, as by welding. While members 30a might be variously formed, they are illustrated as angle bars. Yoke 31 is bent inwardly at its central portion so as to engage member 27 and is connected to member 27 in any suitable manner, as by welding. Member 27 is thus firmly and rigidly secured to the upper end of the support 30. Support 30 also comprises a plurality of bracing members 30b shown as rods extending horizontally between and engaging the sides of bars 30a to which they are connected in any suitable manner, as by welding. A chain 32 is connected to one end of pin 28 and is connected at its other end to one of the bars 30a. In operation when wall 22 is to be built, the bar 20 can be disposed as shown with member 21 disposed in the wall, and the other end of bar 20 will be supported, as shown in Fig. 1, by member 24 and support 30. There will be two or more of the devices and boards or joist-like timbers 34 can be laid on top of members 20 and extend between the same. A very convenient scaffold is formed by members 34 and the operators can stand on this scaffold and continue to build wall 22 upwardly. When the wall is up to a sufficient height, member 21 can be withdrawn from between the bricks 22a and the

space occupied by said member can be filled with mortar or cement. Member 24 can be raised in position and the scaffold can be again positioned at a higher level. It will be noted that support 30 slopes upwardly and toward wall 22. The scaffold can be easily and quickly folded into compact shape when not in use so that it can be easily and conveniently stored or transported. Member 29 can swing about pivot 26 so as to come into substantially parallel relation with member 24.

In Figs. 6 to 8 a different form of ground-engaging support is shown. This support comprises a plurality of elongated members or bars 40, and while these might be variously formed, they are illustrated as upwardly converging angle bars. A vertically extending member 41 is provided and this is illustrated as in the form of a cylinder or pipe. A pair of front bars 40 at one side of the support engage member 41 and will be secured thereto in any suitable manner, as by welding. A brace 42 extends from each of said front bars 40 secured to member 41 and these engage member 41 adjacent the bottom thereof. Members 42 will be secured to front members 40 and to member 41 in any suitable manner, as by welding. The pair of rear bars 40 comprise bar members extending upwardly and having their upper ends engaging member 41. A plate 44 of trapezoidal shape is secured to one side of said rear bars 40 in any suitable manner, as by welding. A pin 45 extends loosely through elongated holes 40a in the outer or remote sides of bar member 40 and is welded to member 41 at its central portion. A rod 46 extends between said latter pair of bars 40 and is in engagement with and is secured to the sides of said bars in any suitable manner, as by welding. A small plate or lug 47 is secured to one side of member 41 at its lower end by welding and said lug is apertured to receive a bolt or rivet 48 which connects it with the upper apertured end of bar 50. Bar 50 extends over rod 46 and is provided at its lower side with a plurality of spaced notches 50a. Bar 50 can be moved so that rod 46 can be disposed in any one of the notches 50a. A U-shaped clip or yoke 51 fits over bar 50 and is slidable on said bar, the same having formed in its downwardly extending sides, notches or slots 51a. When rod 46 is in one of the notches 50a, clip 51 can be slid into position with rod 46 disposed in the slots 51a, as shown in Fig. 6. Rod 50 is thus firmly locked to rod 46 and the rear pair of bars 40 connected to rod 46 are held firmly in one position. With the described structure the rear pair of bars 40 can be moved so that their lower ends are closer to or farther from the lower ends of the other pair of bars. Bars 40 are shown as having circular plates 52 secured to their lower ends in any suitable manner, as by welding. Member 41 is provided at its upper end with a plurality of circumferentially spaced open-ended slots 41a diametrically aligned in pairs.

Due to the fact that pin 45 passes through the elongated holes 40a, a swinging movement of the rear bars 40 connected by plate 44 about member 41 is possible. This capacity of movement enables the foot members 52 on said bars 40 to rest on or engage on uneven surface. These bars 40 therefore adjust themselves to the surface on which foot members 52 rest and so to speak, seek their level. This is quite an important feature. Applicants thus have a four-legged support that will set level and rigid on an un-

even surface. As stated, said rear pair of bars 40 can be swung toward and from the other or front pair of bars 40 by engaging rod 46 in different slots 50a. Said rear pair of bars 40 connected by rod 46 can also be swung close to member 41 so that the scaffold can be collapsed into compact form for storage or transportation. The braces 42, as shown, extend downward from member 41 to the front bars or members 40. This forms an elongated triangle and gives a triangular bracing effect affording great rigidity to the scaffold. This effective bracing renders it possible to use lighter material.

In Figs. 10 and 11 a somewhat different form of support is shown comprising a pair of upwardly extending elongated members 55 shown as in the form of angle bars. A third elongated member 56 also shown as an angle bar extends upwardly toward the upper ends of members 55 and is disposed centrally thereof. A connecting yoke 57 shown as formed from a round rod has its ends bent at right angles and extending through holes in the remote sides of members 55, as shown in Fig. 13. Yoke 57 at its central portion extends around and over a pin or short rod 58 secured centrally to the inner side of member 56 at one side and offset somewhat therefrom at its upper end. (See Figs. 11 and 16.) Members 55 are connected at spaced points by members 59 shown as in the form of angle bars extending therebetween and secured thereto in any suitable manner, as by welding. A vertically extending member 60 is provided projecting above the tops of members 55 and 56 and having secured to one side thereof a short distance below its upper end a plate 61. Plate 61 can be welded to member 60. Plate 61 tapers toward its upper end and is arranged to be engaged by one side of the upper end of member 56. A bolt or rivet 62 pivotally connects member 56 to plate 61. Member 60 is also engaged by the upper ends of members 55, which latter members may be welded thereto. Bracing bars 63 extend between bars 55 and the lower end of member 60, said bars being welded to members 55 and 60. The upper end of member 60, which member is in the form of a cylinder or pipe, is provided with a plurality of vertically extending slots 60a open at their upper ends, said slots being circumferentially spaced and arranged in diametrically aligned pairs. With the construction shown in Figs. 10 to 13, the yoke 57 can readily be removed by lifting its central portion above rod 58 and removing its end portions from bars 55. Bar 56 can then be swung into position substantially parallel with member 60. The support is thus collapsed into much more compact form. This will make it very convenient for transportation.

A rod or pipe 66 is provided and this is adapted to be disposed in and slide in member 41 or member 60. Member 66 is provided with a plurality of vertically spaced holes 66a extending therethrough and a pin 67 can be disposed in any one of holes 66a and have its ends disposed in a pair of aligned slots 41a or 60a. Member 66 has secured to its upper end a plate-like member 68. While member 68 could be variously formed, in the embodiment of the invention illustrated it is shown as comprising a flat bottom wall portion bent upwardly at the center thereof to provide vertically extending portions 68a with their flat sides in engagement and these portions may be connected in any suitable manner, as by welding. Outwardly of each side of this

center wall 68a, the bottom wall portion 68 is again bent up to form the other vertical side walls of a pair of open-ended recesses 68b open at their upper ends and of substantially rectangular form in side elevation. From the upper ends of these other vertical side walls the member 68 is bent outwardly to provide spaced horizontal wall portions 68c the outer ends of which are bent vertically to form relatively narrow flange portions 68d. Portions 68c and 68d thus form a trough-shaped channel. Bracing bars 69 extend downwardly from the lower outer sides of portions 68c to members 66. Bars 69 are welded to member 66 and portions 68c. The recesses 68b can conveniently receive joist-like members or timbers 70 on edge, as shown in Figs. 12 and 14. The portion 68c can conveniently support boards or joist-like timbers 71 in flat position, as shown in Fig. 15. When the timbers 70 are disposed, as shown in Figs. 12 and 14, other boards or timbers 73 can be supported thereby. There will be two or more of the scaffold supports used and timbers 73 will extend between the timbers 70 supported in these two or more of the supports.

From the above description it will be seen that I have provided a very simple and convenient scaffold support. The same can readily be adjusted to support the scaffold or platform at different heights. As described, member 68 can conveniently support timbers or boards both in position on their edges or in flat position. The scaffold platform can thus be readily constructed to suit the specific location and job. The parts of the device are made from standard and easily procured material and the supports can be quickly and inexpensively produced. When the scaffold is set up for use, as shown in Figs. 10 and 12, for work on the walls or ceiling of a building where it is only possible to work at night when the other workmen are absent, the members 66 can be adjusted as desired. When the scaffold must be taken down, the legs can be folded as above described and the members 66 if necessary removed from members 60. When the scaffold is again put up the next evening and members 66 are placed in position, they will come to the same point so that they do not have to be adjusted each time the scaffold is erected. The device has been amply demonstrated in actual practice, found to be very successful and efficient and is being commercially made.

It will of course be understood that various changes may be made in the form, details, arrangement and proportions of the parts, without departing from the scope of applicants' invention, which generally stated, consists in a device capable of carrying out the objects above set forth, in the parts and combinations of parts disclosed and defined in the appended claims.

What is claimed is:

1. A scaffold support having in combination, an elongated vertically extending cylindrical member having a passage therethrough, a pair of bars engaging said member at their upper ends and diverging downwardly therefrom, members rigidly connecting said member and bars, a second pair of bars pivoted adjacent their upper ends to said first mentioned member, the same diverging toward their lower ends and being swingable toward and from said member and first mentioned bars, a third bar pivoted adjacent the lower end of said first mentioned member, a rod extending between said second

pair of bars, said third bar having slots in its lower side, any one of which is adapted to extend over said rod, and a yoke slidable on said third bar having open-ended slots in the sides thereof, said yoke being movable to have said rod disposed within said last mentioned slots and thus lock said last mentioned bar in position.

2. A scaffold supporting device comprising a plate-like member including a bottom wall, opposite vertical side walls and an intermediate vertical wall defining a pair of recesses open at their upper ends for receiving timbers such as 2 x 4's placed edgewise therein from above, said member further including horizontal walls extending laterally from the upper edges of said side walls and terminating in vertical relatively narrow flanges defining a relatively wide shallow channel for receiving a timber such as a plank disposed on one of its sides in overlying relation to said recesses.

3. A scaffold supporting structure having in combination, a support comprising a pair of angularly extending upwardly converging bars, a vertically extending member having a vertical bore therein secured to said bars adjacent the upper ends thereof and projecting thereabove, a bar member pivotally carried by said vertically extending member at the side thereof opposite said pair of bars, means for rigidly holding said bar member in a plurality of spaced diverging positions relative to said vertically extending member, a second vertically extending member slidable in said bore, means for holding said

second vertically extending member in different vertical positions, a plate-like member comprising a bottom wall secured to the top of said second vertically extending member and having opposite vertical side walls and an intermediate vertical wall defining therebetween a pair of timber receiving recesses open at their upper ends, said plate-like member further comprising horizontal walls extending laterally from said side walls, and vertical flanges at the outer ends of said horizontal walls providing a relatively wide channel for receiving a timber in spanning relation to said recesses.

HENRY P. ALBRECHT.
KERMIT H. WILSON.
